UNITED STATES PATENT OFFICE.

CLIFFORD R. WASSELL, OF CHICAGO, ILLINOIS, ASSIGNOR TO HIMSELF, ELMER C. JENSEN, OF CHICAGO, ILLINOIS, WILLIAM H. WINSLOW, OF RIVER FOREST, ILLINOIS, AND CHARLES A. BROWN, OF HINSDALE, ILLINOIS.

OIL-BURNER.

1,274,644.

Specification of Letters Patent. Patented Aug. 6, 1918.

Application filed October 2, 1915. Serial No. 53,684.

To all whom it may concern:

Be it known that I, CLIFFORD R. WASSELL, a citizen of the United States, residing at Chicago, in the county of Cook and State of Illinois, have invented a certain new and useful Improvement in Oil-Burners, of which the following is a full, clear, concise, and exact description, reference being had to the accompanying drawings, forming a part of this specification.

My invention provides an improved oil burner.

In the following specification and accompanying drawings I shall describe and explain a specific type of burner such as is constructed for use under a steam automobile boiler of the Stanley type, but it is distinctly to be understood that this is for the purpose of explaining the principles of my invention and not for limiting the same. While the arrangement of the apparatus is such as to present a maximum of utility in the above situation, it is to be understood that this is to be varied to suit individual conditions.

In burners of this type it is necessary to vaporize the oil and mix it with the air necessary to support combustion and burn the mixture with a blue flame in order to obtain a short hot flame, which will complete combustion within the short distance available in the limited space devoted to this part of the apparatus.

The problem of vaporizing and burning kerosene oil or oils of that type present great difficulties. Due to the greater density and higher boiling point of kerosene, attempts to vaporize and burn said type of oil have been generally unsuccessful—largely because of the tendency of the oil to carbonize with the consequent plugging up of the various parts. Another disadvantage is the objectionable odor which is given off under conditions of incomplete combustion. The high pressure under which the oil is fed and the high temperature under which it is vaporized have heretofore presented almost unsurmountable difficulties in keeping the pipe lines tight.

It is the object of the present invention to provide an oil burner of improved and simplified construction.

It is a further object of the invention to provide an improved pilot burner for use

in connection with the main burner. It is also an object of this invention to provide numerous incidental improvements and especially an improved type of joint for retaining the hot oil and oil vapors.

In the accompanying drawings which form a part of the present specification, I have illustrated as a preferred embodiment of my invention, a main burner with a pilot therefor and the connections from the oil tank to the main burner and to the pilot.

Figure 1 is a plan view of the main burner showing the pilot and oil pre-heater in assembled position.

Fig. 2 is a vertical cross section of the same.

Fig. 3 is a perspective view on an enlarged scale of the capillary tube for conducting the heated oil to the vaporizing surface.

Fig. 4 is a front elevation of the main and pilot burner.

Fig. 5 is a longitudinal vertical cross section of the pilot burner.

Fig. 6 is a front elevation thereof.

Fig. 7 is a side elevation thereof.

Fig. 8 is a vertical cross section taken on the line 8, 8 of Fig. 5.

Fig. 9 is a vertical cross section taken on the line 9, 9 of Fig. 5.

Fig. 10 is a cross section taken through one of the vaporizing tubes and a mixing tube.

Fig. 11 is a detail view showing the vaporizing tubes in cross section and the manner of mounting the ends of the same.

Fig. 12 is a cross section of one of the vapor nozzles or tips and

Fig. 13 is a front elevation similar to Fig. 4 showing the front plate removed for withdrawing the pilot burner.

The problem of constructing an oil burner which is to operate intermittently is complicated by the necessity of keeping the vaporizing surfaces hot during periods when the main burner is not in operation, so that upon a demand for operation of the main burner, the same can immediately be put into service without any especial attention, and without a delay such as would be necessitated by heating the vaporizing surfaces. For this purpose a pilot burner is generally employed and the pilot burner is in constant operation. Due to the small dimensions of the pilot burner and to the limited space in

which it must be confined, and the totally different class of service which it is supposed to furnish, the construction of the pilot burner is radically different from that of the 6 main burner.

The main burner comprises the burner plate or casting 1, which is provided with a series of ridges 2, which have transverse slots 3, cut therein for feeding the mixture 10 of oil vapor and air to the flames in the fire box. The burner plate or casting 1, is surrounded by a circular or cylindrical shell 4, which is preferably constructed of a pair of sheet metal plates 5 and 6 shown more 15 clearly in Fig. 2. The boiler or other object to be heated, which I have shown diagrammatically at 7 in Fig. 2, rests upon the casting 4. The main vaporizing tubes 8 and 9 which are secured at their front ends to the 20 burner block 10, are supported at the rear or back end in a supporting casting 11, which is mounted upon the shell 4. The casting 11 is provided with a pair of sockets 12 and 13 which receive the ends of the tubes 8 and 25 9, the sockets being flared so that the tubes may readily be introduced even though they do not come into exact register with the sockets. The ends of the tubes 8 and 9 are closed by plugs of metal, 14 and 15, which 30 are driven into the open ends of the tubes to make a vapor-tight closure. The plugs are provided with shoulders of about the diameter of the tubes 8 and 9 and are tapered outwardly as shown in Fig. 11 in order to 35 make the introduction of the ends of the tubes into the sockets 12 and 13 as easy and convenient as possible. The tubes 8, 9 are secured in a block 10, either by a driving fit or by a screw thread connection which 40 holds the end of the tube against the edge of the block in order to secure a tight fit. 45 I wish to mention at this point that I have found that no reliance can be placed upon a screw joint for containing the oil vapors, 50 since it is practically impossible to make the internal and external screw threads fit each other perfectly, and the hot oil or oil vapor will find its way through the minutest crevices. 55 The vaporizing tubes 8 and 9 are connected with the nozzles or spuds 16 and 17 which discharge the oil vapors into the corresponding passages 18 and 19 of the vapor and air mixing tubes. 60 The vaporizing tube 9 is connected to its corresponding nozzle 17, through a passage 20, a communicating passage 21 and the tube 23 which connects the spud and the passage 21. The vaporizing tube 8 is connected to 65 its spud 16 in a similar manner, and the passages 20 through the burner block are interconnected by the passageway 22 so that the pressure in the vaporizing tubes and in the spuds may be equalized. 70 The nozzle 17 comprises a block of metal 75 which is tapered conically at its rear end 24 and is hollowed out so as to have a circular bore which connects with the tube 23. The front of the hollow bore is closed off by a machine screw 26, the head of which is forced up against the end of the spud to 80 make a tight fit. The rear end of the spud is pierced by an aperture or orifice for delivering the vapor in a jet at a comparatively high velocity. In order to prevent 85 clogging up of the tip 25, I provide a screen 27 wound in cylindrical form upon the spool 28, the heads 29 and 30 of which fit within the cylindrical bore and close off connection between the pipe 23 and the tip 25 except 90 through the screen 27. The spool 28 is slotted so that the vapor entering at the tube 23 is allowed to pass through the screen 27, through the slots in the spool 28 and out of the bore of the spool to the tip 25. The 95 spool 28 is smaller than the threaded part of the screw 26 so that upon withdrawing the screw 26 the spool and screen may be withdrawn for cleaning purposes. A screw 31 closes a cleaning apertures which is directly in line with the tube 23. With this arrangement of cleaning openings, it is possible to clean not only the tip 25, both from the inside and from the outside, but also to 100 clean out the tube 23 if so desired. 105 The passage 20 is closed at its outer end by a screw 32 so that the passage may be opened and cleaned if so desired. Oil is fed to the vaporizing tubes 8 and 9 through a suitably slotted or reticulated tube of very 110 small bore. One form of the tube 33 is shown on an enlarged scale in Fig. 3. The slot 34 which runs lengthwise of the tube delivers the oil in a very thin film to the bottom of the tube 8 or 9 as the case may be. The tube 115 33 is of such diameter that its entire bore will always be filled when liquid is fed thereto, that is, it is a capillary tube. A beneficial result is obtained thereby for two reasons, first because it will be practically impossible in the arrangement shown for vapor to be trapped in the tube, and second because the contents of the tube is a minimum, and if by accident any trapping should occur, the amount of oil that could be 120 expelled and vaporized would be as small as possible. The vaporization is from the surface of the tubes 8 or 9, as the case may be, where a thin film of the oil is formed, and due to the free surface which this film 125 has, it passes off readily into vapor. The end of the tube 33 is fastened in the block 10 in communication with an oil passage 35 which is clearly shown in Fig. 10. The oil passage 35 of each of the vaporizing tubes connects with a transverse passage 36 which in turn communicates with the oil supply pipe 37 clearly shown in Figs 1 and 13. 130 The supply pipe 37 is connected to a piece of metal tubing, 38, which is preferably

made of some soft metal so as to be slightly flexible. I have found that copper tubing is not entirely suitable and soft steel tubing is preferable. The tube 38 is connected 5 through the valve 39 to the pre-heater 40. The pre-heater 40 consists of a loop or turn of tubing which is placed in the firebox above the main burner 1. This pre-heater tube 40 is arranged on an upward incline 10 from the admission end 41 throughout its entire length to the point of delivery to the valve 39. The pre-heater is placed on an incline so that no trapping of liquid fuel will occur at any point in case of over-heating 15 and formation of vapor within the pre-heater 40. The oil in this pre-heater is to be brought to a temperature slightly below the temperature of vaporization for the given pressure. The pre-heater 40 is provided with an additional loop 42 which lies directly over the pilot burner.

Pilot burner.

The pilot burner which is shown in elevation in Fig. 7 comprises a pilot body casting 43, the bottom of which is V-shaped in order to fit in the central valley or groove of the burner plate 1. The pilot burner is placed directly below the main burner block 10 and 20 the adjacent ends of the vaporizing tubes 8 and 9. The vaporizing tubes are given a slight inclination so that the end adjacent to the block will be the lowest end and any oil which will discharge into the vaporizing tubes 8, 9 will tend to run toward the lower end adjacent to the oil inlet. The pilot burner is placed beneath the lowermost end of the main vaporizing tubes in order to facilitate vaporization, especially upon starting the main burner. The pilot burner comprises a V-shaped pilot body casting 43 having a ridge 44 intersected by suitable kerfs or slots 45 for discharging the mixture of air and vapor to the flames which form 40 above them. The main casting 43 of the pilot burner is cored throughout its length to form a mixing and distributing chamber. A mixing and distributing tube 46 receives the vapor from the nozzle or orifice 47, and 45 mixes the same with the air which is drawn in at the open end of the tube shown at the right of Fig. 5. The bottom of the mixing tube 46 is apertured as shown at 48 and the mixture of air and gas or vapor passes down 50 through the holes 48 and circulates around the outside of the mixing tube 46 and is distributed to the slots 45. The front end 55 of the pilot burner casting shown in Fig. 5 is widened out to give a wider flame from the slots 49 which are set in the top thereof. The slots 49 are placed below the burner block 10 and below the extreme end 60 of the vaporizing tube 50 so as to keep these parts hot in spite of the large surface for 65 radiation which they present.

In order to provide for a proper distribution of the mixture of vapor and air to the slots 45 and 49, I have found it necessary to make special provision for preventing an excess of mixture being fed to the innermost 70 slots 45 and a consequent lack of mixture at the slots 49. The mixing tube 46 is made of a diameter greater than the width of the slots 45 and the left end of this tube as shown in Fig. 5, is raised so that it comes very close to the sides of the casting 43 and forms a restriction for the mixture. As a consequence the inner slots or kerfs, 45, are shut off to a greater or less extent and free 75 passage is provided for the slots 49 so that they will receive their proportionate share of the vapor and air discharged into the mixing tube 46. Due to the velocity of the incoming vapor, the pressure is greater at the innermost end of the mixing tube than 80 it is at the point of entry of the vapor. As a consequence it is necessary to thus restrict the passage to the various slots in order to 85 secure an even distribution of the flame over the top of the burner. The innermost end of the mixing tube 46 fits into a recess which is closed with a plastic mixture such as furnace cement or the like. The bottom of the casting 43 is drilled out to form a 90 passage 51 which communicates by a vertical passage 52 with the vaporizing tube 50. The vaporizing tube 50 is composed of soft steel and is secured with a driving fit into the passage in communication with the channel or passage 52. The vaporizing tube 50 is inclined, as shown, in order to secure a 95 fairly large surface of vaporization without trapping the liquid. The discharge end of the vaporizing tube 50 is fastened with a driving fit into a soft steel block 53 which has a channel, 54, closed at its outer end by the screw 55 which is removable for cleaning purposes. The passage or channel 54 is in communication with a vertical passage 56, the lower end of which is closed by a removable screw 57 for cleaning purposes. This channel 56 communicates with the ori- 100 fice or discharge nozzle 47 which is ar- ranged to be governed by a suitable needle valve, 58, the stem of which projects out through a packing gland 59, and is pro- 105 vided with a square end for adjustment or cleaning. The block 53 being secured to the tube 50 is subject to slight movement due to the expansion and contraction of the 110 vaporizing tube, 50. This block is there- 115 fore seated in a guiding recess in the end of the casting 43 and bodily movements of the block 53, are relieved of straining move- 120 ment by a pin 60 which serves as a guide for preventing tilting of the block 53 when the tube 50 contracts or expands. Expansion and contraction of this tube results in 125 bodily pushing out or withdrawing of the block 53 without disturbing its alignment 130

with respect to the mixing tube 46. The orifice 47 is formed in a removable plug 61 which may be renewed. The bore or channel 51 which receives the oil is connected 5 by a short nipple 62 through a suitable block 63 which has a passage therethrough closed by the removable machine screw 64. A passage at right angles communicates with the tube 65 and the tube 65 in turn 10 communicates with a passage in the union block 66, the passage through which is closed by the screw 67. The block 66 is provided with screw threads at 68 and a tapered conical face at 69, so that the same 15 may be readily united to the oil supply tube 70 (see Fig. 2) which passes under the main burner casing as shown in Fig. 2.

The inner end of the pilot casting 43 is supported in one of the grooves in the main 20 burner casting 1 and the outer end of the casting is provided with grooves 71 and 72 which register with projections 73 and 74 formed in the housing 75 which surrounds the burner block 10 and the outer end of 25 the pilot burner. The burner block 10 is cut away slightly at 76 as shown in Fig. 13, in order to clear the block 53 on the outer end of the pilot.

The front of the housing 75 is covered by 30 a plate 77 which closes off the front and protects the main burner and the pilot burner from leakage of air or drafts. The short tubes or nipples 23 which convey the vapor from the main vaporizing tubes 8 and 9 to 35 the spuds 16 and 17 rest in open slots in the bottom of the housing 75.

The part of the slot which is not filled by the corresponding tube 23 is plugged with cement 78 or the like to make it air-tight, or 40 substantially so. The back part of the housing 75 is provided with a flange 79 which is secured between the plates 5 and 6 of the casing 4. The front plate 77 is provided with an aperture to allow the operator to 45 view the condition of the pilot light and of the main burner, this aperture being normally closed off by a small ornamental plate 80, which is pivoted at 81.

The main vaporizer and the entire pilot 50 burner are readily accessible. By disconnecting the oil supply pipe and loosening the front plate 77 which is held by a pair of screws as shown in Fig. 4, the main vaporizer and the pilot burner may be withdrawn 55 as a unit, or they may be withdrawn separately. The various parts may be then examined and the various passages readily cleaned by removing the machine screws which are stationed at every angle so that 60 cleaning is possible along each and every passage. The joints which I employ between the pieces of tubing and the other parts are made by a driving fit and I find that these joints are perfectly tight even where the 65 connected parts are subjected to heating.

The relative expansion of cast iron and of soft steel of which the parts are composed, is so nearly the same, and the parts are in such close molecular contact, that the joints are not broken by contraction and expansion due 70 to heating, although they may readily be broken, if it is desired to separate the parts.

In the construction of the above burner and pilot, particular attention has been paid to the prevention of any trapping that 75 would be likely to occur in any parts of the oil and vapor passages, and a burner and pilot giving an even and intense heat is the result. Surging in the pilot burner is practically prevented by the inclination of the 80 passages, the passage 51 is formed on an inclination and the passage 50 is a continuation of the same, as a result there is no tendency for the oil to carbonize at any particular point and the passages always remain free 85 and clear.

The arrangement of the Venturi tubes at the ends of the mixing tubes is advantageous in that during service when the vapor is escaping from the orifice in the spuds 16 and 17 90 a maximum quantity of air will be drawn in, due to the high velocity of the jet being placed substantially at the most constricted part of the venturi. When the main burner is shut off and no vapor escaping from the 95 spuds 16 and 17, a minimum amount of air will pass through the mixing tubes and hence the cooling effect upon the vaporizer and the boiler above due to the motion of the car will be a minimum.

It can be seen from the above description that I have provided a burner and a pilot therefore characterized by efficiency, freedom from surging, freedom from carbonization, convenience of manufacture, reliability in 105 action and accessibility for the purposes of adjustment or repair. I have described the burner and pilot as employing kerosene oil but it is to be understood that any other liquid fuel may be employed.

What I claim is:

1. In combination a burner block, a vaporizing tube having communication with said burner block, said tube being closed at one end, a capillary tube having an opening 115 through its side walls for distributing oil to be vaporized along the sides of said vaporizing tube and a burner jet connected to said vaporizing tube through said block.

2. In combination a burner block, a vaporizing tube having communication therewith, a capillary tube lying within said vaporizing tube for supplying oil in a thin film upon said vaporizing tube, said capillary tube having communication through 125 said block, and a burner jet communicating with said vaporizing tube through said block, said vaporizing tube having its inner end closed, said end being raised above the outer end.

3. In combination a burner block, a passage therethrough, a vaporizing tube secured to said block and having communication with said passage, a capillary tube for supplying liquid fuel to said vaporizing tube, said capillary tube being open along its side to deliver oil to said vaporizing tube, said block having a passage therethrough communicating with said capillary tube, said vaporizing tube having one end closed off and the opposite end in communication with a discharge orifice through the said passage in said burner block. 5
4. In combination, a burner, a burner block, a vaporizing tube secured to said block, a burner jet, said jet being in communication with said vaporizing tube, and a tube having a capillary discharge opening on its side for supplying liquid fuel to said vaporizing tube, said vaporizing tube being closed at its outer end and projecting laterally over said burner. 10
5. In combination a burner block having a vapor passage therethrough, an oil passage therethrough, a vaporizing tube embracing both of said passages and being closed at its outer end, and an oil supply tube lying within said vaporizing tube and communicating with said oil passage, said oil supply tube having a relatively minute discharge opening for supplying oil to be vaporized forming a capillary feeding opening. 15
6. In combination a burner block having a pair of vapor passages therethrough, discharge nozzles connected with said vapor passages, said block having an oil passage with orifices adjacent the end of said vapor passages, a pair of vaporizing tubes secured to said block, each of said tubes embracing an oil passage and a vapor passage, said tubes being closed at their outer ends and a capillary tube in each of said vaporizing tubes, lying against the sides thereof and communicating with said oil passage. 20
7. In combination a burner casting, a supporting bracket secured to one side of said casting, a housing substantially diametrically opposite said bracket, said housing secured to the outside of said casting, a burner block in said housing, a vaporizing tube secured to said block and having its inner end closed, 25
8. In combination a burner block, a vaporizing tube secured to said block, said tube being closed at one end, a burner casing, a bracket on said casing, said bracket having a socket adapted to receive the end of said vaporizing tube, a housing secured to said casing diametrically opposite said bracket, said block being secured in said housing, and a front plate for said housing, said plate being removable to allow withdrawal of said block and said vaporizing tube. 30
9. In combination a burner plate having a plurality of slots therethrough, a mixing tube beneath said burner plate, a Venturi passage at the outer end of said mixing tube, said Venturi passage converging to a restricted throat and then diverging to a point of discharge into said mixing tube, and means for delivering a jet of oil vapor to said mixing tube at the Venturi passage. 35
10. In combination a burner plate, a shell surrounding said plate, a vaporizing tube extending substantially diametrically across said casing, a bracket secured to one side of said shell or casing, said bracket supporting one end of said vaporizing tube, said end of the vaporizing tube being closed, a burner block communicating with the opposite end of said tube, a preheater comprising a metallic pipe having a loop adjacent said burner block, said tube being connected to said burner block, and a pilot burner beneath the loop in said tube and beneath said burner block. 40
11. In combination a burner, a housing, a burner block in said housing, a vaporizing tube secured to said burner block, said vaporizing tube projecting over said burner and having its inner end closed, a pilot burner mounted in said housing beneath said burner block, a vapor tube secured to said burner block and having communication with said vaporizing tube, said vapor tube normally resting in a slot in said housing, and a removable front plate for said housing. 45

In witness whereof, I hereto subscribe my name this 28th day of September, A. D. 1915.

CLIFFORD R. WASSELL
